UNITED STATES PATENT OFFICE.

EMMETT T. CORBIN, OF HAMILTON, OHIO.

CONCRETE-COLUMN CLAMP.

Application filed November 17, 1926. Serial No. 148,908.

This invention relates to certain new and useful improvements in concrete column clamps and has for one of its objects to provide a clamp for tightening a metallic strap or band in binding relation with a concrete 5 mold or form for a column.

Another object of the invention is to provide a clamp of the above type wherein the ends of the metallic straps or bands are engaged with the outer ends of a pair of clamping members, with a cam lever for relatively shifting the two clamping members for placing the band in binding and enclosing relations with a column form of mold.

15 A further object of the invention is to provide in connection with a concrete column clamp of the above type, a cam lever forming a part of the clamping mechanism with a cam formation upon each end thereof for 20 selective use whereby the cam lever may assume a different position with respect to the form or mold when moved to its clamping position i. e., to extend either perpendicularly to the mold or be parallel therewith.

25 With the above and other objects in view that will become apparent as the nature of the invention is better understood, the same consists in the novel form, combination and arrangement of parts and in the details of 30 construction hereinafter more fully described, shown in the accompanying drawings and claimed.

In the accompanying drawings, wherein like reference characters indicate corresponding parts throughout the several views,

35 Figure 1 is a fragmentary horizontal sectional view of a mold or form for a concrete column with the clamping device operatively associated therewith, showing the two parts 40 of the clamping device with which the ends of the metallic strap or band are temporarily attached and the cam lever for relatively shifting the two clamping members;

45 Figure 2 is a top plan view of the clamping device with the mold fragmentarily illustrated in side elevation;

Figure 3 is a detail sectional view taken on line 3—3 of Figure 1 showing the two inter-engaged clamping members;

50 Figure 4 is a detail sectional view taken on line 4—4 of Figure 1 showing the cam lever detachably engaged with one of the clamping members with the cam portion thereof disposed for engagement with an abutment on the other clamping member;

Figure 5 is a perspective view of one of the clamping members;

Figure 6 is a perspective view of the other clamping member; and

Figure 7 is a perspective view, partly 60 broken away of the cam lever showing a cam portion at each end thereof.

While the clamping device is capable of association with a concrete column of various cross-sectional configurations, the same 65 is herein illustrated juxtaposed to one side of a rectangular form or mold, and as shown in Figures 1 and 2, the sides of the mold are formed of inter-engaged tongue and grooved boards 1 that are to be retained in 70 position by the batten 2 that is placed in front engagement with the boards 1 with the ends of the batten overlying the outer edges of the end boards. The concrete filling 3 is confined within the matched 75 boards 1.

The gist of this invention resides in the provision of a clamping device for securing in enclosing and binding relations, a metallic strap or band 4 around the mold, the 80 band 4 being first stretched or fully extended in binding relations with respect to the form with the ends of the band secured in holding position by a nail or pin 22 through the clamping device.

85 The clamping device comprises two clamping members and a cam lever with the ends of the band primarily engaged with the outer ends of the clamping members. One 90 of the clamping members shown in detail in Figure 5 comprises a base plate 5 with a rectangular frame at one end projecting perpendicularly therefrom that is formed by bending the end of the base plate to provide spaced vertical walls 6 and 7, a horizontal top wall 8 forming a space 9 between the vertical walls while said vertical walls have aligned openings 10 therein. The upper and lower ends of the opening 10 in the vertical wall 6 are respectively tapered 95 upwardly and downwardly as at 11 to facilitate passage through the openings 10. The outer end of the base plate 5 is provided with an opening 12 through which one end 100 of the band 4 is passed as shown in Figures 105 1 and 2.

The other clamping member which is shown in detail in Figure 6 is of bar formation and comprises an elongated leg 13 of a size to freely pass through the openings 10 110

in the vertical walls 6 and 7 with two parallel rows of spaced openings 14 formed therein. One end of the leg 13 is twisted at right angles to form a head 15 that has an opening 16 therein for the passage of the other end of the band 4. The two clamping members are assembled as shown in Figures 1 and 2 with the leg 13 passed through the openings 10 formed in the rectangular frame at one end of the base plate 5 with the opposite ends of the band 4 passed through the openings 12 and 16 of the clamping members and when so disposed, a clamping lever is cooperatively engaged with the two clamping members and operates to cause the ends of the band to be drawn toward each other.

The clamping lever 17 has cam portions 18 and 19 at opposite ends thereof with oppositely directed pins 20 and 21 carried by each cam portion respectively.

As shown in Figure 1, the leg 13 of one clamping member is passed through the openings 10 in the rectangular frame carried by the ends of the base plate 5 of the other clamping member while the ends of the band 4 are passed through the openings 12 and 16 in the clamping members and extend over and above the ends of the batten 2. The pin 20 projecting from the cam portion 18 of the clamping lever 17 is inserted into one of the lower openings 14 in the leg 13 with the cam portion 18 of the lever disposed for engagement with the adjacent vertical wall 7. The outer end of the clamping lever 17 is then raised and as the cam portion 18 engages the wall 7, the outer ends of the two clamping members are drawn toward each other together with the ends of the band 4 and when the desired tension has been placed upon the band, and to make the same fast, a pin or nail 22 shall be inserted in the space 9 through one of the openings 14, so as to permit removal of the lever 17 leaving all parts of the clamping device in position until the concrete has been poured and set, and retention of the mold boards 1 and batten 2 in position to allow steadyng of the concrete filling 3. When the cam portion 18 of the clamping lever is utilized, the clamping lever assumes a perpendicular position with respect to the batten when the same has been moved to its clamping position and when it is desired to have the clamping lever 17 assume a position parallel with the batten when in its clamping position, the opposite end or cam portion 19 of the lever is employed. The pin 21 carried by the cam portion 19 is inserted in one of the openings 14 of the upper row in the leg 13 and by moving the outer or cam portion 18 of the clamping lever in a direction toward the batten 2, the ends of the two clamping members are similarly drawn toward each other for plac-

ing the retaining band 4 under tension. The pins 20 and 21 extend from opposite sides of the clamping lever to permit the latter to be disposed at either side of the leg 13 as will at once be appreciated from an inspection of Figures 2 and 4.

While there is herein shown and described the preferred embodiment of the present invention it is nevertheless to be understood that minor changes may be made therein without departing from the spirit and scope of the invention as claimed.

What I claim as new is:

1. In a concrete column clamp, a pair of lapping clamping members constructed for temporary attachment of the ends of a band and a cam lever detachably connected to one clamping member and engaged with the other clamping member at the lapping parts to cause separating movements of the lever engaged parts of the members and movements of the band ends toward each other.

2. In a concrete column clamp, a pair of clamping members constructed for temporary attachment of the ends of a band, said members lapping each other and an abutment on the lapping end of one member, and a cam lever detachably connected to one member and moved into engagement with the abutment on the other member to cause relative separating movements between the lever engaged parts of the two members for drawing the band ends toward each other.

3. In a concrete column clamp, a pair of clamping members constructed for temporary attachment of the ends of a band and a cam lever detachably connected to one clamping member and engaged with the other clamping member to cause relative movements therebetween and movements of the band ends toward each other, and said lever having a cam portion at each end, the clamping lever lying adjacent the column when one cam end is active and being spaced from the column when the other cam end is active.

4. In a concrete column clamp, a pair of clamping members constructed for temporary attachment of the ends of a band, said members being interengaged and an abutment on one member, and a cam lever detachably connected to one member and moved into engagement with the abutment on the other member to cause relative movements between the two members to draw the band ends toward each other, and said lever having a cam portion at each end, the clamping lever lying adjacent the column when one cam end is active and being spaced from the column when the other cam end is active.

5. In a concrete column clamp, a pair of clamping members constructed for temporary attachment of the ends of a band and a cam lever detachably connected to one clamping member and engaged with the

- other clamping member to cause relative movements therebetween and movements of the band ends toward each other, the connection between the lever and clamping member 5 including a pin carried by the lever and one of said clamping members having series of openings therein for the selective reception of the pin.
6. In a concrete column clamp, a pair of 10 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, said lever having a cam portion at each end, the clamping lever lying adjacent the column when one cam end is active and being spaced from the column 15 when the other cam end is active, the engagement between said members including a housing carried by one member forming an abutment for the cam lever and having an opening therethrough, and the other member having a leg extending through the housing opening.
7. In a concrete column clamp, a pair of 20 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, the connection between the lever and clamping member including a 25 pin carried by the lever, and one of said clamping members having series of openings therein for the selective reception of the pin.
8. In a concrete column clamp, a pair of 30 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, the engagement between said members including a housing carried by one member forming an abutment for the cam lever and having an opening therethrough, and the other member having a leg extending through the housing opening.
9. In a concrete column clamp, a pair of 35 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, the connection between the lever and clamping member including a pin carried by the lever and one of said clamping members having series of openings therein for the selective reception of the pin.
10. In a concrete column clamp, a pair of 40 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, said lever having a cam portion at each end, the clamping lever lying adjacent the column when one cam end is active and being spaced from the column 45 when the other cam end is active, the engagement between said members including a housing carried by one member forming an abutment for the cam lever and having an opening therethrough, and the other member having a leg extending through the housing opening.
11. In a concrete column clamp, a pair of 50 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, said lever having a cam portion at each end, the clamping lever lying adjacent the column when one cam end is active and being spaced from the column 55 when the other cam end is active, the engagement between said members including a housing carried by one member forming an abutment for the cam lever and having an opening therethrough, and the other member having a leg extending through the housing opening.
12. In a concrete column clamp, a pair of 60 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, the engagement between said members including a housing carried by one member forming an abutment for the cam lever and having an opening therethrough, and the other member having a leg extending through the housing opening.
13. In a concrete column clamp, a pair of 65 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, the engagement between said members including a housing carried by one member forming an abutment for the cam lever and having an opening therethrough, and the other member having a leg extending through the housing opening.
14. In a concrete column clamp, a pair of 70 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, the engagement between said members including a housing carried by one member forming an abutment for the cam lever and having an opening therethrough, and the other member having a leg extending through the housing opening.
15. In a concrete column clamp, a pair of 75 clamping members constructed for temporary attachment of the ends of a band, said members being interengaged and an abutment on one member, a cam lever detachably connected to one member and moved into engagement with the abutment on the other member to cause relative movements between the two members to draw the band ends toward each other, the engagement between said members including a housing carried by one member forming an abutment for the cam lever and having an opening therethrough, and the other member having a leg extending through the housing opening.

In testimony whereof I affix my signature.
EMMETT T. CORBIN.
